DESIGN FOR A LIQUID PUMP

Wilbur Miller, Lima, and Ira I. Swallow, near Lima, Ohio

Application May 31, 1935, Serial No. 57,081

Term of patent 7 years

To all whom it may concern:

Be it known that we, Wilbur Miller and Ira I. Swallow, citizens of the United States, residing, respectively, in the city of Lima, in the county of Allen and State of Ohio, and in the county of Allen, near the city of Lima, and State of Ohio, have invented a new, original, and ornamental Design for Liquid Pumps, of which the following is a specification, reference being had to the accompanying drawing, forming part thereof.

The figure is a perspective view of a liquid pump, showing our new design.

We claim:

The ornamental design for a liquid pump, as shown.

WILBUR MILLER.
IRA I. SWALLOW.
